GUY L. FITCH, OF METROPOLIS, ILLINOIS

REINFORCED WOODEN BOW AND METHOD OF MANUFACTURE THEREOF

Application filed July 13, 1929. Serial No. 378,140.

This invention relates to a wooden bow for vehicle tops and to a method of manufacture of such a bow.

The principal object of the invention is to provide a metal reenforcement for a wooden bow having said reenforcement inset in the inner side of the bow, although certain features of the method of manufacture are equally applicable to a bow having the reenforcement in any other desired relation to the wooden member.

The principal features of the invention reside in the bow itself and in the novel method of manufacturing said bow wherein the metal reenforcement is set in place before the bending of the wood structure and the wood and metal are then simultaneously bent to the desired shape.

The full nature of the invention will be understood from the accompanying drawings and the following description and claims.

Fig. 1 is a view of the wooden portion of the bow prior to bending showing in dotted line the position of a receiving slot for the reenforcing piece. Fig. 2 is a sectional view taken on the line 2—2 of Fig. 1. Fig. 3 is a view illustrating the shape of the reenforcing piece before insertion into the receiving slot illustrated in Fig. 1. Fig. 4 is an elevational view of the completed bow. Fig. 5 is a perspective view of the completed bow. Fig. 6 is a sectional view showing an alternative positioning of reenforcing members.

In the manufacture of the bow, a piece 10 of the proper type of lumber is first shaped as shown in Fig. 1. A groove or rabbet 11 is then cut in one edge of the wooden member as indicated in Fig. 1 and Fig. 2. A piece of 40 steel or other reenforcing material 12, shaped as illustrated in Fig. 3, is then placed in the slot 11 and secured in place by a plurality of screws 13. The whole assembly is then heated in hot water or a steam retort to give the 45 proper pliancy to the wooden member. After heating, the assembly is bent by any common form of wood bending machine into the shape illustrated in Fig. 4. The usual finishing processes are then applied to the wood work 50 and the bow is completed.

There are obvious advantages in placing the metal reenforcement in the position contemplated herein. First, the metal is in the proper place to receive the tensile stress due to any tendency for the ends of the bow to 55 spring outward. Second, since the reenforcing member has its longest dimension in the vertical direction, it is in the proper position for adequately resisting any vertical bending strain in the bow. Third, the reenforcing 60 member, by being placed at one side of the bow as illustrated in Fig. 2, is not in position to interfere with tacks or screws which will be used in fastening fabric covering to the upper or under side of the bow. Fourth, by the use 65 of a continuous reenforcing member extending completely across the top of the bow around the corners and a substantial distance down each leg of the bow, the entire bow is 70 thoroughly reenforced. It is obvious that 75 such a reenforcing piece could not be inserted in the wooden member after bending without carrying the slot 11 to the extreme ends of the bow. Since these ends are preferably made of a tapering shape, such an extension of the 75 slot would greatly weaken the ends.

If desired, a plurality of reenforcing members may be used positioned as shown in Fig. 6 wherein 110 illustrates the wooden portion and 112 indicates two reenforcing members.

The invention claimed is:

1. The process of manufacture of a reenforced bow including the shaping of a wooden member with a groove in one side terminating short of its ends, the securing of a reenforcing piece therein, and the simultaneous bending of the wooden member and reenforcing member to the desired bow shape with the reenforcing member on the inner edge of the bow and extending a substantial distance along 80 the legs of the bow.

2. The process of manufacture of a reenforced bow including the shaping of a wooden member with a groove in one side terminating short of its ends, the securing of a reenforcing piece therein, and the simultaneous bending of the wooden member and reenforcing member to the desired bow shape with the reenforcing member on the inner edge of the bow.

3. The process of manufacture of a reen-

forced bow including the shaping of a wooden member with a groove in one side, the securing of a reenforcing piece therein, and the subsequent simultaneous bending of the wooden member and reenforcing piece to the desired bow shape with the longest cross-sectional dimension of the reenforcing piece substantially perpendicular to the inner edge of the bow.

10 In witness whereof, I have hereunto affixed
my signature.

GUY L. FITCH.
